CLAIM

The ornamental design for a light-irradiating beauty apparatus, as shown and described.

DESCRIPTION

FIG. 1 is a front view of a light-irradiating beauty apparatus; FIG. 2 is a right side view thereof; FIG. 3 is a top plan view thereof; FIG. 4 is a rear view thereof; FIG. 5 is a left side view thereof; FIG. 6 is a bottom plan view thereof; FIG. 7 is a sectional view thereof taken along line 7-7 of FIG. 1, in which the internal components are omitted; FIG. 8 is a perspective view thereof showing a state where a hand-held is detached from a main body; FIG. 9 is a front perspective view of the hand-held of the light-irradiating beauty apparatus; FIG. 10 is a rear perspective view thereof; FIG. 11 is a front view thereof; FIG. 12 is a right side view thereof; FIG. 13 is a top plan view thereof; FIG. 14 is a rear view thereof; FIG. 15 is a left side view thereof; FIG. 16 is a bottom plan view thereof; and, FIG. 17 is a sectional view thereof, taken along line 17-17 of FIG. 11, in which the internal components are omitted. The features shown in broken lines depict environmental subject matter only and form no part of the claimed design. The main body of the light-irradiating beauty apparatus has been omitted from the disclosure in FIGS. 9 to 17 for convenience of illustration.
